US00D856685S

(12) **United States Design Patent** (10) **Patent No.:** **US D856,685 S**
Burditt et al. (45) **Date of Patent:** **** Aug. 20, 2019**

(54) **COSMETICS BRUSH WITH RECTANGULAR FERRULE**

(71) Applicant: **HCT GROUP HOLDINGS LIMITED**, Central (CN)

(72) Inventors: **Stephen C. Burditt**, Los Angeles, CA (US); **Tania Miren Diaz**, Santa Monica, CA (US)

(73) Assignee: **HCT GROUP HOLDINGS LIMITED**, Hong Kong (HK)

(**) Term: **15 Years**

(21) Appl. No.: **29/665,165**

(22) Filed: **Oct. 1, 2018**

Related U.S. Application Data

(62) Division of application No. 29/609,831, filed on Jul. 6, 2017, now Pat. No. Des. 833,156.

(57) **CLAIM**

The ornamental design for a cosmetics brush with rectangular ferrule, as shown and described.

DESCRIPTION

FIG. 1 is a perspective view of an embodiment of a cosmetics brush with a rectangular ferrule;

FIG. 2 is a front elevation view of the embodiment of the cosmetics brush with the rectangular ferrule from FIG. 1, the back elevation view being identical to the front elevation view;

FIG. 3 is a left side elevation view of the embodiment of the cosmetics brush with the rectangular ferrule from FIG. 1, the right side elevation view being identical to the left side elevation view;

FIG. 4 is a top plan view of the embodiment of the cosmetics brush with the rectangular ferrule from FIG. 1; and,

FIG. 5 is a bottom plan view of the embodiment of the cosmetics brush with the rectangular ferrule from FIG. 1. The brush head shown in broken lines in the drawings is environmental in structure and forms no part of the claimed design.
